UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

STEAM BOILER.

Original application filed April 15, 1919, Serial No. 290,180. Divided and this application filed December 23, 1922. Serial No. 608,716.

To all whom it may concern:

Be it known that I, DAVID S. JACOBUS, a citizen of the United States, residing at Jersey City, in the county of Hudson and State of New Jersey, have invented certain new and useful Improvements in Steam Boilers, of which the following is a specification.

In the drawing, Fig. 1 is a vertical transverse section through a boiler showing one embodiment of my invention; Fig. 2 is a section on the plane of the line 2—2 of Fig. 1, and Fig. 3 is an enlarged section through the down-take headers to illustrate the method of staggering.

The present application is a division of my copending application Serial No. 290,180, filed April 15, 1919.

Referring to the drawing, the numeral 1 designates an upper bank of horizontally inclined water tubes, and 2 a corresponding lower bank shown as comprising three rows. The combustion chamber 3' below the lower bank of tubes extends substantially the entire length of the tubes, the boiler being fired at both front and rear by underfeed stoker mechanisms 3 of well known construction. The lower ends of the tubes of alternate vertical rows of the upper bank are connected to downtake headers 4 and 5, and the upper ends of said tubes are connected to uptake headers 6 and 7, while the lower ends of the tubes of alternate vertical rows of the lower bank are connected to header sections 8 and 9, and the upper ends of said tubes are connected with drop-leg extensions 6' and 7' of the uptake headers 6 and 7. The headers 4 and 5 are connected to the header sections 8 and 9, respectively, by relatively long nipples 10 and 11, and the upper ends of the headers 4 and 5 are connected to a transverse steam and water drum 12 by nipples 13 and 14. Said drum is also connected to the uptake headers 6 and 7 by two rows of horizontal tubes 15. A baffle 16 extends over the upper row of tubes 2 from the header sections 8 and 9 for a portion of their length, and a transverse baffle 17 divides the upper bank of tubes into two passes. The space between headers of superheater 25 is closed by a baffle 50', and the horizontal spaces between the upper headers and between the lower headers of the two superheaters are closed

by the usual baffle blocks laid on the superheater tubes between each pair of headers. The gases will flow over the banks of tubes in the general direction indicated by the arrows to the outlet connection 18, the latter delivering the gases to an uptake flue 60 in which is located an economizer comprising a series of horizontal boxes 19 connected by tubes 20. This economizer may constitute the high pressure stage of an economizer system, the low pressure stage 65 of which is not shown. The tubes and boxes of the economizer are preferably of wrought iron or wrought steel to withstand the high boiler pressure to which they are subjected. As shown, it is divided into 70 three sections, water entering the uppermost section through the pipe 21 and leaving said section through the pipe 22, by which the water is delivered to the middle section and leaves the latter through the pipe 23, which 75 delivers it to the lowermost section, from which the water flows through a pipe 24 to the steam and water drum 12.

By arranging the economizer in the way described, the advantages of the counter-flow principle are secured, as the uppermost of the three sections which comes in contact with the coolest gases will contain the coolest water, the middle section which comes in contact with the gases of an intermediate temperature, somewhat hotter water, and the third and lowermost section which comes in contact with the hottest gases, will contain the hottest water. Each section is fed at the lower part and the heated water passes 80 away from the upper part. This results in the water flowing upwardly throughout each section which gives a more even distribution between the different tubes than should the water be fed downwardly through 85 the sections. Again, by feeding the water upwardly throughout each section in the way described, the water flowing through each tube flows in a slightly upward direction and tends to more thoroughly sweep out 90 any air or contained gases from the tubes than would be the case should there be a downward flow.

A primary superheater 25 is preferably located in the triangular space above the upper bank of tubes, and a secondary superheater 26 is located in the secondary combustion chamber between the two banks of

- tubes, the steam from the drum 12 being delivered through the pipe 27 to the superheater 25 and from the latter through a pipe 28 to the upper box of the superheater 26.
- 5 The superheated steam is delivered to the main through a connection from the lower box 26' of the superheater 26. A second superheater 29 is also located in the secondary combustion chamber between the two banks 10 of tubes, to the upper cross-box of which steam is delivered from one of the stages of a steam turbine, and the steam so re-superheated, returned through a connection from the cross-box 29' to a lower pressure section of the turbine. In order to completely flood the superheater loops between the banks, these loops are related to the boxes in such a way that no air will be trapped in the loops as the water rises in 15 the superheater tubes. It will also be noted that the superheater tubes may be drained after they have been flooded, by permitting the water to pass out through the boxes. In the particular construction shown, therefore, the superheater can be both flooded and drained. This is of special advantage in the case of the superheaters between the banks; since under certain conditions of service, it may be necessary to completely 20 flood the loops to prevent burning them in starting up the boiler when no steam is flowing through the superheater. The nearer the superheater tubes are to the combustion chamber, the more important it is to flood 25 them. Also the loops for the superheaters 26 and 29 should be so proportioned that they can be introduced by passing them between the nipples 10 and 11.
- In the drawing, I have shown a staggered 30 arrangement of the headers whereby headers having a greater width than the distance between the tubes measured horizontally may be employed, and thus enabling the use of a heavier construction of header for a given tube diameter than is possible where the headers are arranged in the same plane. For example, if a boiler for exceptionally 35 high pressure is desired, a header that would normally be used for a four-inch diameter tube could be made of the same outside dimensions but with thicker walls and could be employed for a three-inch tube. Should all of the headers when constructed in this way be placed in the same plane, the spaces 40 between the three-inch tubes for the passage of the gases would be wider than they should be for the best operation and efficiency. By overlapping the headers the proper spaces for the passage of the gases 45 is secured between the tubes. With the staggered and overlapping arrangement of the headers, I provide means for calking the spaces between the headers to secure a gas-tight joint, as by placing asbestos or 50 other plastic material 48 between the head-

ers and holding such material in position by special pieces 49, in the form of angle-irons, bent to fit the stagger of the headers. The pieces 49 may be held by fluted struts 50, which, after being placed in position and being struck, will be extended and made to bear tight against the pieces 49.

By the arrangement described, the staggered arrangement of the nipples 10 and 11 can be secured with straight nipples instead 55 of using curved nipples, as described in a companion application. Also, the staggered arrangement of the nipples 13 and 14 which connect the steam and water drum 12 with the headers 4 and 5 results in the 60 cutting away of a less amount of metal in a longitudinal line measured along the drum thereby giving greater strength for a given drum thickness than is possible with all of the nipples arranged in the same 65 plane.

I claim:

1. A water tube boiler having front and rear vertically extending water compartments connected by two banks of horizontally inclined water tubes, the banks being spaced apart to provide a chamber of a height as great as that of a plurality of rows of the water tubes of the upper bank, baffling for directing the products of combustion, said baffling having a longitudinal baffle extending from the lower ends of the water tubes above a plurality of rows of water tubes to expose the major portion of their length and allow a free and unobstructed entrance of the gases to the chamber at the higher ends of the tubes, and an upwardly projecting baffling means extending from the inner end of the horizontally 90 extending baffle transversely of the water tubes above the chamber, a superheater located in said chamber and having boxes at the rear of a plane extending through the front headers provided with superheater tubes having return bends within the boiler 95 setting, a furnace below the water tubes and extending substantially the length of the water tubes, and a pair of stoker mechanisms projecting from the front and rear walls into the lower part of the furnace 100 below the water tubes.

2. A water tube boiler having front and rear vertically extending water compartments connected by two banks of horizontally inclined water tubes, the banks being 105 spaced apart to provide a chamber of a height as great as that of a plurality of rows of the water tubes of the upper bank, baffling for directing the products of combustion, said baffling having a longitudinal baffle extending from the lower ends of the water tubes above a plurality of rows of water tubes to expose the water tubes below 110 said baffle to the flame and gases for the major portion of their length and allow a free 115

- and unobstructed entrance of the gases to the chamber at the higher ends of the tubes, and an upwardly projecting baffling means extending from the inner end of the horizontally extending baffle transversely of the water tubes above the chamber and inclined to the vertical to restrict the upward flow of the gases, a superheater located in said chamber and having boxes at the rear of 10 a plane extending through the front headers provided with superheater tubes having return bends within the boiler setting, a furnace below the water tubes and extending substantially the length of the water tubes, 15 and a pair of underfeed stoker mechanisms projecting from the front and rear walls into the lower part of the furnace below the water tubes.
3. A water tube boiler having front and 20 rear vertically extending water compartments connected by two banks of horizontally inclined water tubes, the banks being spaced apart to provide a chamber of a height as great as that of a plurality of rows 25 of the water tubes of the upper bank, baffling for directing the products of combustion, said baffling having a longitudinal baffle extending from the lower ends of the water tubes above a plurality of rows of water 30 tubes to expose the water tubes below said baffle to the flame and gases for the major portion of their length and allow a free and unobstructed entrance of the gases to the chamber at the higher ends of the tubes, and 35 an upwardly projecting baffling means extending from the inner end of the horizontally extending baffle transversely of the water tubes above the chamber, a superheater located in said chamber and having boxes at 40 the rear of a plane extending through the front headers provided with superheater tubes having return bends within the boiler setting, a furnace below the water tubes and extending substantially the length of the water tubes, and a pair of underfeed stoker 45 mechanisms projecting from the front and rear walls into the lower part of the furnace below the water tubes, the lower portion of the chamber between the banks of water 50 tubes being unobstructed by cross baffling to provide for turning of the stream of heated gases within said chamber after the second or down pass of said gases on their way to the outlet.
- 55 4. A steam boiler having a furnace arranged to give an unobstructed primary combustion chamber extending the entire distance between the front and rear walls of the furnace, horizontally inclined water tubes extending across the furnace chamber, 60 said tubes being arranged in spaced apart banks and with the lowermost tubes exposed for substantially their entire length to the radiant heat of the furnace, a superheater in the space between the banks of water tubes with the superheater tubes 65
- ter tubes, a pair of underfeed stoker mechanisms disposed on either side of the central vertical plane of the furnace with their grates inclined toward each other, a horizontal baffle extending from the lower ends 70 of the water tubes longitudinally of the water tubes and above a plurality of rows of said tubes, and a transverse baffling means extending upwardly from the inner end of the longitudinal baffle.
5. A steam boiler having a furnace arranged to give an unobstructed primary combustion chamber extending the entire distance between the front and rear walls of the furnace, horizontally inclined water 80 tubes extending across the furnace chamber, said tubes being arranged in spaced apart banks and with the lowermost tubes exposed for substantially their entire length to the radiant heat of the furnace, a superheater in the space between the banks of water tubes, a pair of underfeed stoker mechanisms disposed on either side of the central vertical plane of the furnace with their grates inclined toward each other, a horizontal baffle extending from the lower ends 85 of the water tubes longitudinally of the water tubes and above a plurality of rows thereof, and a transverse baffling means extending upwardly from the inner end of the longitudinal baffle and across water tubes above the superheater space.
6. A steam boiler having a furnace arranged to give an unobstructed primary combustion chamber extending the entire 100 distance between the front and rear walls of the furnace, horizontally inclined water tubes extending across the furnace chamber, said tubes being arranged in spaced apart banks and with the lowermost tubes exposed 105 for substantially their entire length to the radiant heat of the furnace, a U-tube superheater in the space between the banks of water tubes, a pair of underfeed stoker mechanisms disposed on either side of the central vertical plane of the furnace with their grates inclined toward each other, a horizontal baffle extending from the lower ends 110 of the water tubes longitudinally of the water tubes and above a plurality of the rows thereof, and an inclined transverse baffling means extending upwardly from the inner end of the longitudinal baffle.
7. A steam boiler having a furnace arranged to give an unobstructed primary combustion chamber extending the entire distance between the front and rear walls of the furnace, horizontally inclined water tubes extending across the furnace chamber, 120 said tubes being arranged in spaced apart banks and with the lowermost tubes exposed for substantially their entire length to the radiant heat of the furnace, a U-tube superheater in the space between the banks of water tubes with the superheater tubes 125
- 130

extending in the same general direction as the water tubes, a pair of underfeed stoker mechanisms disposed on either side of the central vertical plane of the furnace with their grates inclined toward each other, a horizontal baffle extending from the lower ends of the water tubes longitudinally of the water tubes and above a plurality of the rows thereof, and a transverse baffling means 5 extending upwardly from the inner end of the longitudinal baffle and across the water tubes of the upper bank.

10. A steam boiler having a furnace arranged to give an unobstructed primary combustion chamber extending the entire distance between the front and rear walls of the furnace, horizontally inclined water tubes extending across the furnace chamber, said tubes being arranged in spaced apart 15 banks and with the lowermost tubes exposed for substantially their entire length to the radiant heat of the furnace, a superheater in the space between the banks of water tubes, a pair of underfeed stoker mechanisms 20 symmetrically disposed on either side of the central vertical plane of the furnace with their grates inclined toward each other, a horizontal baffle extending from the lower ends of the water tubes longitudinally of the water tubes and above a plurality of rows of said tubes, and a transverse baffling means 25 extending upwardly from the inner end of the longitudinal baffle.

8. A steam boiler having a furnace arranged to give an unobstructed primary combustion chamber extending the entire 30 distance between the front and rear walls of the furnace, horizontally inclined water tubes extending across the furnace chamber, said tubes being arranged in spaced-apart banks and with the lowermost tubes exposed 35 for substantially their entire length to the radiant heat of the furnace, a superheater in the space between the banks of water tubes and having looped tubes arranged so that they can be flooded with water, a pair 40 of underfeed stoker mechanisms disposed on either side of the central vertical plane of the furnace with their grates inclined toward each other, a horizontal baffle extending from the lower ends of the water tubes longitudinally of the water tubes and above a plurality of rows of said tubes, and a

transverse baffling means extending upwardly from the inner end of the longitudinal baffle.

10. A steam boiler having a furnace arranged to give an unobstructed primary combustion chamber extending the entire distance between the front and rear walls of the furnace, horizontally inclined water tubes extending across the furnace chamber, 60 said tubes being arranged in spaced-apart banks and with the lowermost tubes exposed for substantially their entire length to the radiant heat of the furnace, a superheater in the space between the banks of water tubes 70 and having looped tubes arranged so that they can be flooded with water and drained, a pair of underfeed stoker mechanism disposed on either side of the central vertical plane of the furnace with their grates inclined toward each other, a horizontal baffle 75 extending from the lower ends of the water tubes longitudinally of the water tubes and above a plurality of rows of said tubes, and a transverse baffling means extending 80 upwardly from the inner end of the longitudinal baffle.

11. A water tube boiler having front and rear vertically extending water compartments connected by two banks of horizontally inclined water tubes, the banks being spaced apart to provide a chamber of a height as great as that of a plurality of rows of the water tubes of the upper bank, baffling for directing the products of combustion, said baffling having a longitudinal baffle extending from the lower ends of the water tubes above a plurality of rows of water tubes to expose the water tubes below 95 said baffle to the flame and gases for the major portion of their length and allow a free and unobstructed entrance of the gases to the chamber at the higher ends of the tubes, and an upwardly projecting baffling means extending from the inner end of the 100 horizontally extending baffle transversely of the water tubes above the chamber, a superheater located in said chamber and having boxes at the rear of a plane extending through the front headers and provided 105 with superheater tubes having return bends within the boiler setting, the tubes of the superheater being arranged so that they can be flooded with water, and a furnace below the water tubes and extending substantially 110 the length of the water tubes.

DAVID S. JACOBUS.
